UNITED STATES PATENT OFFICE.

OTTO W. SCHAUM, OF PHILADELPHIA, PENNSYLVANIA, ASSIGNOR TO SCHAUM & UHLINGER, INCORPORATED, OF PHILADELPHIA, PENNSYLVANIA, A CORPORATION OF PENNSYLVANIA.

LOOM.

1,278,226.

Specification of Letters Patent. Patented Sept. 10, 1918.

Application filed January 15, 1917. Serial No. 142,416.

To all whom it may concern:

Be it known that I, OTTO W. SCHAUM, a citizen of the United States, and a resident of Philadelphia, county of Philadelphia, State of Pennsylvania, have invented new and useful Improvements in Looms, of which the following is a specification.

The invention relates to looms and particularly narrow-ware looms employing two or more banks or rows of shuttles arranged with the rows one above another.

In my Patent No. 786,237 granted March 28th, 1905, and in my Patent No. 803,511 granted October 31st, 1905, there is shown a narrow-ware loom of the type just referred to. In this class of looms it is advisable that any of the several rows or banks of shuttles be positioned with respect to the open shed of the loom so that the yarn or threads carried by said banks or rows of shuttles may be woven in the fabric.

In looms of this type there is employed a lay-beam or a batten-beam as it is called that extends longitudinally along the forward part of the loom and the several banks of shuttles extend along and are located above said beam. The batten-beam and the banks of shuttles associated therewith reciprocate horizontally and transversely, or in other words forward and back. The banks of shuttles are also capable of being moved vertically, relative to the batten-beam, and are mounted so that they can be moved horizontally and longitudinally when depositing the threads.

The present invention is directed to a new construction for supporting the batten-beam and for maintaining the banks of shuttles, when in any one of the desired positions, in proper position relative to the batten-beam.

The novel features above referred to as well as other novel features are hereinafter specifically described and definitely pointed out in the accompanying claims.

As illustrating a specific form of the invention reference is made to the accompanying drawings forming a part of this specification, in which drawings,

Figure 1 is a partial vertical sectional view showing a portion of an end or transverse frame, a lay-head, and some of the parts for supporting and actuating the lay-head.

Fig. 2 is a partial front view or elevation showing a portion of the end or transverse

frame, a portion of the lay-head, and some of the parts for supporting and actuating the lay-head.

Fig. 3 is a vertical sectional view of the lay-head which comprises the batten-beam, 60 the shuttle carrying frame and a casting for supporting said batten-beam and frame.

Fig. 4 is a sectional view of the lay-head casting with certain attached parts omitted. This is a view of the casting when taken as 65 on the line 4-4 of Fig. 1 looking in the direction of the arrows.

Fig. 5 is a view taken as on the line 5-5 Fig. 3 looking in the direction of the arrows.

Fig. 6 is a perspective view of a detail 70 which is on the shuttle carrying frame.

The lower portion of an end or transverse frame 1 of the loom is clearly shown in Fig. 1. The lay-head of the loom is designated by 2 and is shown as being provided with 75 four rows or banks of shuttles, a, b, c and d. The lay-head comprises a batten-beam or lay-beam 3, a frame 4 carrying the shuttles, mechanism associated therewith whereby the shuttles can be carried in said frame and 80 can also be operated, and a lay-head casting 5 the function of which casting will hereinafter more fully appear. As the batten-beam 3 and the frame 4 is each a comparatively long member there are employed a 85 plurality of these castings, at least one at each end of the machine, and there may be intermediate castings if required to impart rigidity and strength to the associated members. Each lay-head casting 5 is carried by 90 parallel links 6 and 7. The lower end of each of these links is pivotally mounted upon a suitable bearing carried by the frame 1 and in the form shown this bearing is provided on a member 8 which is secured to the 95 end or transverse frame 1 in any suitable manner. The upper end of the link 6 is pivotally connected at 9 to the lower forward portion of the casting 5 and the upper end of the link 7 is pivotally connected at 10 to 100 the lower back portion of the casting 5. This casting 5 is shown more in detail in Fig. 3 in which figure it will be observed the batten-beam 3 is secured in place upon the casting by means of a bolt 11. Vertical ad- 105 justment of this batten-beam, is attained through the medium of an adjusting screw 12 which is locked in place by means of a nut 13.

A depending leg or spacing member 14 ex- 110

2
tends from the under side of the batten-beam 3 into a socket 15 and rests upon the upper end of the adjusting screw 12. At the rear side of the lay-beam or batten-beam there is 5 secured in any suitable manner a plate or member 16. This plate or member is also secured, when the batten-beam is in adjusted position, to the upper end of the casting 5 by means of bolts 17, clearly shown in 10 Fig. 5.

The shuttle carrying frame 4 comprises a pair of vertically spaced longitudinally extending beams 18 which are connected together by means of vertically extending tie members 19 whereby a comparatively rigid frame construction is formed. This frame 4 is located above and extends along the lay-beam or batten-beam 3, as previously stated. The casting 5 comprises a horizontally and 15 transversely forwardly extending portion 20—the portion in which the adjusting screw 12 is located—and a vertically extending portion 21, both of which portions are integral with each other or in other words 20 constitute a part of the same casting.

The portion 21 extends above the top of the batten-beam 3 behind the frame 4 just described and serves to receive any backward thrust which is imparted to it through 30 the parts which will be hereinafter more fully described. In other words, the construction is such that the forces necessitated by the moving of the frame forward and backward are all absorbed by this casting.

35 The frame 4 has been heretofore described as being vertically movable relative to the batten-beam. This is taken care of by means of a vertically extending guide-member 22, preferably made of cold rolled steel, which 40 is carried in sockets or drilled openings 23 and 24 in the casting 5. This vertically extending guide-member 22 can be readily removed by lifting it out of the position shown. The frame 4 is provided at its top 45 and bottom with ear members or lugs 25 and 26 which have a sliding engagement with said guide-member 22. The ear members or lugs 25 may be referred to as the vertically movable guide-members since they 50 move vertically along and relatively to the vertically extending guide-member 22 which is a relatively stationary member. These ears or movable guide-members are shown in perspective in Fig. 6. As constructed the 55 lower end of the vertically extending guide-member 22 rests upon the bolt 11 which serves as a stop or support for said guide-member. The lay-head casting 5 is cut out at 27 to permit vertical movement of the 60 bolt as the batten-beam 3 is vertically adjusted.

The batten-beam 3 has heretofore been described as resting upon the top of the spacing member 14 which engages the upper 65 end of the adjusting screw 12. Prac-

tically any desired height of adjustment of the batten-beam can be attained by the employment of the spacing members 14 of the proper selected length. The lay-head casting may be considered as of L-shape with 70 the lower or transversely extended portion of the L extending forwardly under the batten-beam. The upwardly extending portion of the L, as previously pointed out, extends upwardly past the batten-beam and 75 behind the shuttle carrying frame 4. At each end of the lower transversely extending member or portion there are provided drilled openings 28 and 29 through which pins 30 and 31, at points 9 and 10 heretofore referred to, pass whereby the lay-head casting is supported by the upper ends of the parallel links 6 and 7. This casting also has another drilled opening 32 through which passes a pin 33 that connects a link 34 which 80 extends from the mechanism that moves back and forth the lay-head casting and associated parts, or what may be referred to as the operating mechanism.

The mechanism for accomplishing this 85 movement is old and well known in the art and hence is not further described.

During the normal operation of the loom it is frequently desirable to raise and lower the frame 4 carrying the shuttles whereby 90 any particular bank or row of shuttles can be brought into operative position relative to the open shed.

Pattern controlled mechanism (or in fact other forms of mechanism for accomplishing this movement) is old and well known in the art and hence is not described herein. The movement from this mechanism to the shuttle carrying frame has heretofore been accomplished by means comprising levers, 100 links or the like. In the construction shown the motion from the pattern controlled mechanism to the frame is transmitted from the mechanism through an arm 35, only part of which is shown—link 36, lever or 105 rocker 37, and link 38 which is connected to the frame 4 by means of bearing members 39 which are secured to the frame 4. The lever or rocker 37 is secured to a rod or shaft 40 which may be referred to as a 110 rocker shaft. The arms 37—if there are more than one in a long machine—may be referred to as lifting arms which are secured to the rod or shaft 40; they are manifestly a part of the lever or rocker mechanism 37. The rod or shaft 40 extends longitudinally of the machine and is carried on bearings that are on the end or transverse frames of the machine. There may also be provided a cantaliver spring or 115 springs 41 which can be secured either to the lever or rocker 37 or the rocker shaft 40 to which the lever 37 is secured. The free end of this spring 41 rests upon a bearing 42 on the floor. This spring serves as a 120

means to counterbalance the weight of the links 38, the frame 4 and the parts carried by the frame. The arrangement of the levers and links for operating the shuttle carrying frame differs somewhat from the constructions heretofore employed and, therefore, has been clearly shown and described in this application.

The arm 35 may be considered a part of or as actuated by the pattern controlled mechanism. The link 38 is made adjustable in length by the employment of a turn-buckle arrangement 43 or double or oppositely threaded screw construction whereby the height or vertical position of the frame 4 relative to the batten-beam 3 can be regulated. The shuttles are carried in the frame 4, as indicated, and can be operated by longitudinally movable racks which are also carried in the frame and which are operated by mechanism well known in the art.

A suitable construction whereby shuttles can be moved by means of this rack is shown in U. S. patent to Wagner No. 473,563, granted April 26th, 1892, for swivel loom. Such being old, the shuttles, racks and operating mechanism whereby the racks may operate the shuttles are not illustrated in detail on the drawings.

The improvements herein set forth are not limited to the precise construction and arrangement shown and described for they may be embodied in various forms and modifications without departing from the spirit and scope of the invention.

Having thus described my invention what I claim and desire to secure by Letters Patent of the United States is:

1. A loom comprising in combination with parallel links attached at the lower ends to the loom frame, batten beams, a set of shuttles, and means for raising and lowering said set of shuttles, of a lay-head casting carried by the upper end of said parallel links which casting has and comprises as a part thereof, a forwardly extending member and a vertically extending member, and which casting carries a vertically extending bolt which passes through said forwardly extending member, whereby vertical adjustment can be imparted to the batten-beam, the set of shuttles being provided with means which slidably engage a guide on the vertically extending member, and said guide.

2. A loom comprising in combination with the parallel links that are attached at the lower ends to the loom frame, a batten-beam, banks or rows of shuttles and means for raising and lowering said banks of shuttles, of a lay-head casting carried by the upper ends of said parallel links, which casting has and comprises as a part thereof a forwardly extending member and a vertically extending member, means carried by said forwardly extending member of the

casting for vertically adjusting the position of the batten-beam, and a vertically extending guide-member supported by the vertically extending member of the casting in such a manner that backward thrust imparted to the vertically extending guide-member will be received by the vertically extending member of the casting which is located behind the guide-member and also behind the banks of shuttles, said banks of shuttles having means engaging the vertically extending guide-member.

3. A loom comprising in combination with parallel links attached at the lower ends of the loom frame, a batten-beam, rows or banks of shuttles and means for raising and lowering said banks of shuttles, of a lay-head casting carried by the upper ends of said parallel links and to which lay-head casting the batten-beam is connected, said lay-head casting comprising a vertically extending member which extends upwardly beyond the batten-beam and behind the banks or rows of shuttles which are located above the batten-beam, and a guide member, said banks of shuttles being provided with means that slidably engage said guide-member which guide-member is on and is carried by the vertically extending member of the casting in such a manner that any backward thrust received by the guide-member will be imparted to the vertically extending member of the casting.

4. A loom comprising in combination with end or transverse frames, parallel links supported on said frames, a longitudinally extending batten beam, a frame carrying banks of shuttles located above and extending along said batten-beam, of lay-head castings each of which is carried by a pair of the parallel links at the upper end of said links, means engaging said castings for imparting forward and backward movement to said castings, and an associated means for raising and lowering the frame carrying the banks of shuttles each of said castings having a forwardly extending member and an upwardly extending member which members are integral with each other, an adjusting screw for each casting which adjusting screw passes through the forwardly extending member and serves to vertically adjust the batten-beam, the vertically extending member of the lay-head casting having a vertically extending guide-member, and the frame carrying the banks of shuttles having ears which engage said guide-members.

5. A loom comprising in combination an end or transverse frame, parallel links supported by said frame, a lay-head casting supported by the upper ends of said links, a batten-beam secured to said casting, a vertically extending guide-member mounted upon and carried by a portion of said casting, which casting extends upwardly at the

rear of the batten-beam and behind said guide-member, a frame carrying a set of shuttles, said frame having members which slide along said guide-member, means for imparting a forward and backward movement to said casting, and means for imparting a vertical movement to said frame carrying the shuttles.

6. A loom comprising in combination an end or transverse frame, parallel links supported thereupon, a lay-head casting carried by said links at the upper end of the links, a longitudinally extending batten-beam secured to said casting in a manner to permit a vertical adjustment of the batten-beam, means for effecting said vertical adjustment of the batten-beam when desired, means for imparting a forward and backward movement to said casting, a frame carrying banks or rows of shuttles with one row of shuttles arranged above another, said casting having an integral part which extends upwardly behind said shuttle carrying frame and provided with a vertically extending guide-member which is located behind said shuttle carrying frame, said shuttle carrying frame having a vertically movable guide member engaging said vertically extending guide-member, and means for imparting vertical movement to said shuttle carrying frame.

7. A loom having in combination with the end or transverse frames thereof, sets of parallel links supported thereby, each set of links carrying an L-shaped lay-head casting, a guide means, a batten-beam secured to said lay-head castings, a shuttle carrying frame located over said batten-beam and slidable upon said guide means, which lay-head castings extend upwardly past the batten-beam and behind the shuttle carrying frame, so as to support the latter against backward thrust, a shaft extending longitudinally of the loom and mounted in bearings on said end or transverse frames, rocker arm or lever mechanism carried by said shaft, links connecting said rocker arm

or lever mechanism and said shuttle carrying frame, and mechanism for actuating said lever mechanism.

8. A loom comprising in combination with the end or transverse frames thereof, of a rocker shaft carried in bearings on said frames, sets of parallel links carried upon said frames, lay-head castings carried by said links, each of which lay-head castings has a vertically extending guide-member, a batten-beam secured to and carried by said lay-head castings, a shuttle carrying frame located above said batten-beam which shuttle carrying frame slides vertically along said vertically extending guide-members, lifting arms carried by said shaft and links connecting said lifting arms to said shuttle carrying frame, means for actuating said shaft whereby vertical movement can be imparted to said shuttle carrying frame, and means for actuating the lay-head castings back and forth.

9. A loom comprising in combination end or transverse frames, a rocker shaft carried by said frames, parallel links carried by said frames, lay-head castings carried by said links, each of which lay-head castings has thereupon a vertically extending guide-member, a batten-beam secured to said lay-head castings, vertically extending screw means carried by said castings for vertically adjusting said batten-beam, a shuttle carrying frame slidable on said vertically extending guide-members, lifting arms carried by said shaft and links adjustable in length for connecting the free ends of said arms to said shuttle carrying frame, means for imparting forward and backward movement to said lay-head castings, and means for raising and lowering the free ends of said arms.

This specification signed and witnessed this 11th day of January, A. D. 1917.

OTTO W. SCHAUML.
